UNITED STATES PATENT OFFICE.

JEROME JOSEPH SCHOTTEN, OF ST. LOUIS, MISSOURI.

MACHINE FOR PASTING AND FOLDING CARTONS.

No. 877,744.

Specification of Letters Patent.

Patented Jan. 28, 1908.

Application filed May 31, 1907. Serial No. 376,614.

To all whom it may concern:

Be it known that I, JEROME JOSEPH SCHOTTEN, a citizen of the United States, residing at St. Louis, Missouri, have invented a certain new and useful Improvement in Machines for Pasting and Folding Cartons, of which the following is a full, clear, and exact description, such as will enable others skilled in the art to which it appertains to make and use the same, reference being had to the accompanying drawings, forming part of this specification, in which,—

Figure 1 is a top plan view of a machine constructed in accordance with my invention; Fig. 2 is a side elevation of the machine shown in Fig. 1; Fig. 3 is a vertical cross sectional view taken on the line 3—3 of Fig. 1; Fig. 4 is a vertical cross sectional view taken on the line 4—4 of Fig. 2; Fig. 5 is an enlarged perspective view of the folding box; and Fig. 6 is a perspective view of one of the cartons upon which the machine is designed to operate.

This invention relates to machines for pasting and folding cartons formed from pliable material, such, for example, as cardboard.

The main object of my invention is to provide a machine of simple construction which will automatically fold and paste together the end flaps of a partially formed cardboard carton.

Referring to the drawings which represent the preferred form of my invention, A designates what I will term the "folding box" and 1 designates a conveyer herein shown as an endless belt for carrying the carton through the folding box. The belt 1 surrounds pulleys 2 and 3 located at the opposite ends of the machine and the pulley 2 is secured to the main power shaft 4 which drives the paste-applying apparatus, as hereinafter described.

In Fig. 6 I have illustrated a carton provided at each end with two side flaps 5 and 6 and a top and bottom flap 7 and 8 which are folded over and pasted together as the carton is fed through the folding box A by the conveyer 1; and in Fig. 5 I have illustrated in detail the folding box. This folding box comprises a top member composed of two sections 9 and 9^a and a bottom member also composed of two sections 10 and 10^a, the object in forming these top and bottom members in sections being hereinafter ex-

plained. Said top and bottom members are held spaced away from each other by vertically disposed bars 11 and 11^a connected thereto. At the front end of this folding box is a pair of approximately wedge-shape folding plates 12 secured to the top and bottom members before referred to and at the rear of said plates and forming parts of the sides of the box A is another pair of folding plates 13 secured to the side faces of the bottom member. A third pair of folding plates 14 which also form parts of the sides of the box, is secured to the upper member at the rear of the folding plates 13. On the lower edge portions of the side faces of the bottom member of the box adjacent the front end thereof are laterally projecting lugs 15 and on the upper edge portions of the sides of the top member are laterally projecting lugs 16 which extend from the front end of said top member to a point adjacent the folding plates 14. These lugs 15 and 16 act as spacers for guide plates 17, the lower edges of which are inclined and are spaced away from the folding plates 13 so as to produce longitudinally extending inclined slots 18, said guide plates also forming parts of the sides of the box A.

The guide plates are provided at their front ends with depending portions 17^a which are secured to the lugs 15 on the bottom member but this is the only point at which the guide plates are secured to the bottom member. The front ends 13^a and 14^a of the pairs of folding plates 13 and 14 are mortised into the side faces of the bottom and top member of the box so that no abrupt shoulders will be formed at the points where the front ends of said folding plates terminate.

The carton is adapted to form a wrapper for a bag or sack containing spires or any other substance and after the bag has been slipped into the carton the flaps 5 at each end of the carton are folded inwardly by the fingers of the operator, as shown in Fig. 6. The carton is then inserted between the wedge-shaped folding plates 12 and this operation of inserting the carton causes said plates to bend the flaps 6 at each end of the carton inwardly so that they will overlap the flaps 5 that were bent inwardly by the fingers of the operator, see Fig. 5. Only one of the folding plates 12 is shown in Fig. 5 but it will, of course, be understood that a pair of such plates is provided as shown in Fig. 1, one of

the plates 12 having been omitted from Fig. 5 so as to more clearly illustrate the construction of the folding box.

As previously stated, the carton is fed 5 through the folding box by the conveyer 1 and to this end said conveyer is provided with lugs or blocks 1^a which engage the carton and cause it to move with the conveyer.

As the carton travels between the folding 10 plates 12 said plates will bend the flaps 7 and 8 at each end of the carton into a vertical position, as shown in Fig. 5, said flaps thereafter passing into the guideways or channels formed by spacing the guide plates 17 away 15 from the top and bottom member of the box.

After the carton has reached the position indicated by the carton x in Fig. 5 so that the flaps 7 have passed from under the depending portions 17^a of the guide plates, paste or some 20 other suitable adhesive substance is applied to the inside faces of the flaps 7.

The means herein shown for applying paste to the flaps 7 consists of horizontally disposed disks 19 arranged adjacent the side faces of the lower member of the box A, as 25 shown in Fig. 3, so that the flaps 7 will come into contact with said disks during the forward movement of the carton and thus receive a coating of paste. The paste is supplied to the disks 19 by vertically disposed disks 20 which contact with the peripheral edges of the disks 19 and also extend into hoppers or tanks 21 that contain a supply of paste. The shafts 22 to which the horizontal 30 disks are secured are mounted in stationary bearings 23 and are provided at their upper ends with beveled gears 24 that mesh with beveled gears 25 on a horizontal cross shaft 26 mounted in a bearing 27, the bearings 23 and 27 being secured to the top member of 35 the folding box A. Continuous rotary movement is imparted to the cross shaft 26 by means of a belt 28 passing over a pulley 29 on said cross shaft and over a pulley 30 on the main drive shaft 4. The vertical disks 20 which convey the paste from the supply tank 40 to the applying disks 19 are secured to a horizontal shaft 31 mounted in a bearing 32 on the underneath side of the bottom member 45 of the folding box, and at one end of said shaft is a sprocket wheel 33 which receives a chain 34 that travels over a cog wheel 35 on the cross shaft 26 whereby continuous rotary movement will be imparted to the vertical disks 20.

After paste has been applied to the inside faces of the flaps 7, as just described, said flaps are bent upwardly over the ends of the folded flaps 5 and 6. This is effected by the 50 folding plates 13 whose upper edges are inclined upwardly, said plates also being provided with outwardly flared portions 13^b, as shown in Fig. 5. As the flaps 7 come into contact with the inclined edges of the flared portions 13^b the flaps will first be bent into a

horizontal position and then gradually bent upwardly as the carton is fed along by the conveyer as indicated by the carton y in Fig. 5. After the carton has traveled past the flared portions 13^b of the folding plates the 70 bottom flaps 7 will bear against straight portions of the plates 13 which will hold said flaps firmly down upon the folded side flaps 5 and 6, as indicated by the carton z in Fig. 5, thereby permitting the paste to set so that 75 the flaps 7 will be retained in this position. The top flaps 8 of the carton were bent upwardly by the folding plates 12, as previously described, and when the carton entered the space between the upper and lower members 80 of the folding box said flaps passed into the grooves or channels between the guide plates and the top member of the box. The flaps 8 are retained in this position until the carton reaches the folding plates 14 which are of 85 similar construction to the plates 13 except that the edges of the outwardly flared portions 14^b are inclined in an opposite direction to those of the plates 13 so that the flaps 8 will first be bent outwardly and then downwardly over the flaps 7, as indicated by the carton w shown in dotted lines in Fig. 5. Prior to bending down the flaps 8 the inner faces of said flaps were coated with paste by a paste-applying apparatus of the same construction as that previously described and consisting of horizontally disposed applying disks 36, vertical conveying disks 37, and tanks 38 for holding a supply of paste, the cross shaft 39 which imparts movement to 90 the disks being driven by means of a chain 40 passing around sprocket wheels 26^a and 39^a on the ends of the cross shafts 26 and 39. 95

The flaps 8 are subjected to pressure after they have been folded inwardly so as to cause 100 the paste to set and thus retain them in position by means of two endless belts 41 which form a guideway for the carton, as shown in Fig. 1, and spring-pressed plates 42 that bear upon said belts and force them inwardly 105 against the ends of the carton.

The belts 41 travel around pairs of pulleys 43 and 44, the pulleys 43 being secured to shafts provided with beveled gears 45 that mesh with beveled gears 46 on the shaft of 110 the pulley 3 over which the conveyer 1 travels. The plates 42 which bear upon the belts 41 are movable toward and away from each other and the flat springs 47 which exert yielding pressure on said plates are fastened 115 at their outer ends to stationary supports forming part of the frame work of the machine. In order that the belts 41 may lie snugly against the sides of the top and bottom members of the folding box A near the 120 rear end thereof, the bars 11^a which connect said top and bottom members together are bent outwardly, as shown in Fig. 5, to provide a passageway for the belts.

During the time the cartons are traveling 125

through the folding box the top sides of said cartons are subjected to the pressure or weight of a long plate 48 which prevents the carton from bulging, said plate having its front end curved upwardly at 49 so that it will rest on the top member of the box and thus form a fulcrum for the plate 48.

From the foregoing it will be seen that the operation of pasting and folding the flaps of the carton is entirely automatic, the cartons with their flaps open, as shown in Fig. 6, being fed into the machine by an operator who stands adjacent the wedge-shaped plates 12 and being automatically ejected from the machine by the conveyer 1 after the flaps have been pasted and folded. The machine is of such simple construction that it can be manufactured at a small cost and is not liable to get out of order and does not require any skill on the part of the operator who runs it.

Another desirable feature of the machine is that it can be used for pasting and folding the flaps of cartons of various sizes and it is for this purpose that I form the upper and lower members of the folding box in sections.

As shown in Fig. 5, the strips or bars 49^a which connect the two sections of the top member together are provided with elongated slots through which screws 50 extend so that by loosening said screws the sections can be moved toward or away from each other and then again clamped by tightening the screws, thereby permitting the width of the folding box to be varied. The bars 11, 35 and 11^a which secure the top and bottom members of the box together are also provided with elongated slots through which screws extend so that the height of said box can also be varied, and the folding plates 12, 40 13 and 14 are provided with elongated slots through which the screws extend to secure them in position, thereby enabling said plates to be adjusted. The adjustment of the folding box will necessarily necessitate 45 an adjustment of the paste-applying apparatus and to this end I have formed the conveying and applying disks and also the driving gears so that they can be adjusted on the shafts on which they are mounted, the 50 hubs of said disks and gears being provided with set screws for this purpose.

Having thus described my invention, what I claim as new and desire to secure by Letters Patent is:

55 1. In a machine for pasting and folding the end flaps of a carton, a conveyer for holding the carton, a stationary member for folding in some of the flaps of the carton as it is introduced into the machine, means for applying an adhesive substance to other flaps of the carton, and means for folding said flaps over the flaps which were folded inwardly when the carton was introduced into the machine; substantially as described.

60 2. In a machine for pasting and folding

the end flaps of a carton, a conveyer for holding the carton, means for bending some of the flaps of the carton into an approximately vertical position so that they extend at right angles to the body of the carton, 70 means for applying an adhesive to the inside faces of said flaps, and means for thereafter bending said flaps into their final position; substantially as described.

3. In a machine for pasting and folding 75 the end flaps of a carton, a movable conveyer on which the carton is placed, a folding apparatus comprising stationary plates for folding inwardly some of the side flaps of the carton, said plates also bending the top and 80 bottom flaps into an approximately vertical position, means for applying an adhesive to the bottom flaps, stationary means for thereafter folding said bottom flaps inwardly and pressing them upon the side flaps, means 85 for applying an adhesive to the top flaps, and means for thereafter bending said top flaps into final position; substantially as described.

4. In a machine for pasting and folding 90 the end flaps of a carton, a conveyer on which the carton is placed, and a folding box through which said conveyer travels, said folding box being provided with stationary plates which bend some of the side flaps in- 95 wardly and the top and bottom flaps into an approximately vertical position to receive an adhesive as the carton is inserted in the machine, plates which bend the bottom flaps upwardly over the side flaps, and plates which 100 thereafter bend the top flaps downwardly into final position; substantially as described.

5. In a machine for pasting and folding the end flaps of a carton, a conveyer for folding the carton, a folding box through which 105 said conveyer travels, wedge-shaped folding plates at the front end of said box for folding inwardly some of the side flaps of the carton and also bending the top and bottom flaps into approximately vertical position, a guide plate for retaining said flaps in a vertical position, and plates provided with outwardly flared portions having inclined edges for progressively bending the top and bottom flaps of the carton into final position as the conveyer moves it through the box; substantially 110 as described.

6. In a machine for pasting and folding the end flaps of a carton, a conveyer for carrying the carton, and a folding box 120 through which said conveyer travels, said folding box comprising top and bottom members formed in sections that are adjustably connected together, and adjustable side plates which are so constructed that they will 125 progressively fold in the flaps of the carton as it travels through the box; substantially as described.

7. In a machine for pasting and folding the end flaps of a carton, a conveyer on which 130

- the carton is placed, means for bending some of the flaps of the carton into position to receive an adhesive, horizontally disposed disks for applying an adhesive to said flaps, 5 vertically disposed disks for conveying the adhesive to said applying disks, and means for rotating said disks; substantially as described.
8. In a machine for pasting and folding 10 the end flaps of a carton, a conveyer for carrying the carton, means for bending some of the flaps of the carton into an approximately vertical position, horizontally disposed disks for applying an adhesive to said 15 flaps, vertically disposed disks for conveying the adhesive to the peripheral edges of said applying disks, and tanks for holding the adhesive and through which said vertical disks travel; substantially as described.
- 20 9. In a machine for pasting and folding the flaps of a carton, a conveyer for holding the carton, means for applying paste to some of the flaps of the carton, means for folding the flaps into final position, a guideway through 25 which the carton is adapted to travel after

its flaps have been folded into final position, and means for causing the walls of said guideway to exert pressure on the folded flaps of the carton; substantially as described.

10. In a machine for pasting and folding 30 the end flaps of a carton, a conveyer on which the carton is placed, a folding box constructed to fold the flaps of the carton into final position as the conveyer moves it through the box, means for applying an ad- 35hesive to some of the flaps of the carton prior to the operation of folding them into position, a plurality of belts located at the rear of the folding box and forming a guideway for the carton, and spring-pressed plates 40 bearing upon said belts to exert pressure upon the folded flaps of the carton; substan- tially as described.

In testimony whereof I hereunto affix my signature in the presence of two witnesses, 45 this twenty-eighth day of May, 1907.

JEROME JOSEPH SCHOTEN.
